UNITED STATES PATENT OFFICE

GLOYD L. SEIFERT, OF HOLYOKE, COLORADO

COMBINED STARTER SWITCH AND CHOKE

Application filed February 4, 1929. Serial No. 337,361.

My invention is a combined starter switch and choke for motor vehicles and an object of the invention is to provide a device which will serve as the usual choke rod and as a circuit closer for controlling an electrical circuit to the usual starter.

Further the invention provides a device of this character which will permit a circuit to the starter to be completed without choking the carburetor; permit the usual choke valve to be adjusted to any desired position while the motor is in operation; and it may also be operated to actuate the choke valve to full open position prior to completion of the 15 starter circuit.

With the preceding and other objects and advantages in mind the invention consists in the novel combination of elements, constructions and arrangements of parts and operations to be hereinafter specifically referred to, claimed and illustrated in the accompanying drawings wherein;

Figure 1 is a fragmentary vertical section view of part of a motor vehicle with my invention associated therewith;

Fig. 2 is a longitudinal sectional view taken on line 2—2 of Fig. 1, the broken lines indicating the device in full choking position; and

Fig. 3 is a transverse section taken on line 3—3 of Fig. 2.

Referring to the invention in detail a cylindrical casing is provided comprising a pair of tubular sections 5 and 6 having telescopic engagement and each of which is formed with a cup-shaped member 7 at its outer end. Annular flanges 8 are formed on each of the sections and extend circumferentially around the same.

To secure the casing in place a plurality of bolts 9 extending longitudinally of the casing pass through the flanges at spaced intervals and through the usual dash board 9. Pairs of jam nuts 11 are threaded upon the 45 bolts and engage the opposite faces of the flanges. Similar nuts 11^a are also threaded upon the bolts and engage the inner face of the dash board.

A substantially frusto-conical hood 12 is 50 arranged in longitudinal alignment with the

casing and is provided with an annular flange 13 at its inner end which is secured to a similar annular flange 14 formed on the adjacent end of the cup-shaped member 7 of the section 6. A forwardly extending tubular 55 guide 15 extends from the forward end of the hood through which the usual choke valve operating cable 16 extends.

A choke rod 17 extends centrally and longitudinally through the casing and is slidably supported by the end walls of the cup-shaped members. One end of the choke rod extends into the hood 12 and is connected with the cable 16 by a coil spring 18. The opposite end of the choke rod passes through 60 the dash board is equipped with the usual operating handle 19.

For the purpose of completing an electrical circuit to the usual motor vehicle starter a contact plate or switch member 20 is received on the choke rod at a point within the confines of the casing and is secured thereto by washers 21 suitably held on the choke rod and engaging the opposite faces of the contact plate. Suitable insulation 23 is provided 70 for insulating the contact plate from the washer 21 and choke rod.

A pair of spaced contacts 24 project from the inner face of the end wall of each of the cup-shaped members 7 and are suitably insulated therefrom by insulating material 25 which alines the cup-shaped members. The contacts 24 are formed with binding posts 26 which project laterally from the outer faces of the end walls of the cup-shaped members 80 and are connected together in series by conductor wires 27. A pair of feed wires 28 having electrical connection with the usual starter, not shown, are connected with one pair of the binding posts. Thus with the choke rod in either of its extreme positions the contact plate 20 will engage one pair of the contacts 24 to complete an electrical circuit through the starter.

With my invention it will be observed that 95 the circuit to the starter will be completed upon longitudinal movement of the choke rod in either direction. Thus upon forward thrust of the choke rod the circuit to the starter will be completed without choking the 100

carbureter. In choking the carbureter the contact plate will complete the circuit subsequent to the full choking of the carbureter. That is to say, when the parts reach the broken line position shown in Fig. 2 the choke valve will have reached its full open position so that upon continued movement of the choke rod the circuit to the starter will be completed. These operations are possible by reason of the elastic or spring connection 18 between the choke rod and cable 16.

For the purpose of retaining the choke rod against rotation so that the contact plate 20 will always be in longitudinal alignment with the spaced contacts 24 a pair of parallel guide bars 29 are supported longitudinally within the casing from one of the cup-shaped members 7. As particularly disclosed in Fig. 3 these guide bars 29 are located upon opposite sides of the choke rod and pass through slot 30 in the contact plate. Thus the choke rod and contact plate 20 will always move in a true longitudinal direction and at the same time be prevented from rotating.

25 What is claimed is:

1. In a combined choke actuating device and circuit closer, a support, pairs of longitudinally aligned spaced contacts, a choke rod slidable on the support, and a contact member carried thereby and engageable with either pair of contacts.

2. In a combined choke actuating device and circuit closer, a support, pairs of longitudinally aligned spaced contacts, a choke rod slidable on the support, a contact member carried thereby and engageable with either pair of contacts, and an elastic element connected with one end of the choke rod and adapted to operatively connect with a choke operating cable.

3. In a combined circuit closer and choke actuating device, a casing to be mounted upon the dash of an automobile, pairs of spaced contacts carried by the ends thereof, a choke rod slidably mounted in the casing, and a contact member carried thereby and engageable with either pair of contacts.

4. In a combined circuit closer and choke actuating device, a casing to be mounted upon the dash of an automobile, pairs of spaced contacts carried by the ends thereof, a choke rod slidably mounted in the casing, a contact member carried thereby and engageable with either pair of contacts, and a spring carried by the inner end of the choke rod adapted for connection with a choke control whereby to permit the choke rod to move in opposite directions a predetermined distance without affecting the choke cable with which the spring is connected.

5. In a combined choke and circuit closer, a casing embodying a pair of telescopically engaged members, means for supporting such members from the dash of an automobile, a pair of contacts arranged at each end of the

casing, a choke rod slidably mounted in the casing, and a contact carried thereby and engageable with either pair of the first mentioned contacts.

6. In a combined choke and circuit closer, 70 a tubular casing, parallel flanges formed on the periphery of the casing, a plurality of fastening members extending longitudinally of the casing at spaced intervals and secured to the flanges and adapted to have connection with a fixed part of an automobile, pairs of contacts in the casing, a choke rod longitudinally movable through the casing, and a contact movable therewith and engageable with either pair of the first mentioned contacts.

7. In a combined choke and circuit closer, 85 a tubular casing, parallel flanges formed on the periphery of the casing, a plurality of fastening members extending longitudinally of the casing at spaced intervals and secured to the flanges and adapted to have connection with a fixed part of an automobile, pairs of contacts in the casing, a choke rod longitudinally movable through the casing, and a contact movable therewith and engageable with either pair of the first mentioned contacts, and parallel guides extending longitudinally within the casing and having 90 slideable engagement with the movable contacts.

Signed at Holyoke, in the county of Phillips and State of Colorado, this 30th day of January, A. D. 1929.

GLOYD L. SEIFERT.
